UNITED STATES PATENT OFFICE

JACOB S. ALLEN, OF PHILADELPHIA, PENNSYLVANIA

PAN-GREASING MACHINE

Application filed September 4, 1925. Serial No. 54,527.

This invention is a pan greasing apparatus, and among its several objects is to provide an improved apparatus for use in bake shops to grease simultaneously the interiors of a set of pans; to provide for conveniently and uniformly supplying grease to a series of rotating brushes to which the interiors of the pans may be conveniently applied; to provide for reversing the rotation of the 10 brushes at regular intervals so as to maintain the bristles of the brushes in their proper and effective condition; to provide for conveniently blowing out the grease passages should such passages become 15 obstructed; to provide for conveniently heating the grease and for uniformly distributing the same to the series of brushes; to provide for conveniently adjusting the brushes with respect to one another so as to adapt the 20 apparatus to pans of different sizes; and to provide for the convenient removal and replacement of any one or more of the brushes without disturbing any of the other brushes and without requiring any dismantling of 25 any of the other parts of the apparatus.

With these and other objects in view, the present invention consists in the combination and arrangement of parts as will be herein-after more fully described, illustrated in the 30 accompanying drawings and particularly pointed out in the appended claims, it of course being understood that changes in the form, proportion, size and minor details may be made, within the scope of the claims, 35 without departing from the spirit or sacrificing any of the advantages of the invention.

In the drawings:

Figure 1 is a side elevation of a pan greasing apparatus embodying the features of the 40 present invention.

Figure 2 is a plan section on the line 2—2 of Figure 1.

Figure 3 is an enlarged fragmentary detailed sectional view on the line 3—3 of 45 Figure 2.

Figure 4 is a vertical cross-sectional view on the line 4—4 of Figure 1.

Figure 5 is an enlarged vertical sectional view of one of the brushes and its mounting 50 on the line 5—5 of Figure 1.

Figure 6 is an enlarged detailed sectional view on the line 6—6 of Figure 1.

Figure 7 is a detail view illustrating the cover plate arrangement permitting adjustment of the brush bearings.

The frame of the present apparatus includes four leg standards 1 each of which is an angle bar. The leg standards at each end of the frame converge upwardly and are connected to a head 2 in the form of a single casting which is provided on its outer face with a handle 3 for convenience in moving the machine. The corresponding legs at opposite ends of the frame are connected by a lower angle bar 4 and an intermediate angle bar 5. Suitable braces 6 extend between intermediate portions of each intermediate bar 5 and the leg standards 1 so as to brace and stiffen the frame. A horizontal shelf or partition 7 extends throughout the length and width of the frame and constitutes a support for certain portions of the apparatus.

Angle bars 8 and 9, located one above the other, extend longitudinally along the top of the frame and are secured at their ends to bracket members 10 extending inwardly from the castings 2. These angle bars are disposed with their vertical sides in alignment and spaced to provide a longitudinal slot 11. Mounted to slide endwise on top of the upper angle bar 8 is a rack bar 12, which has vertical teeth 13 on the front face of the rack bar. Bearing members 14, in the form of fiber blocks are interposed between the angle bar 8 and the rack bar 12, one of such bearing blocks being well shown in each of Figures 5 and 6 of the drawings. The rack bar 12 is slidably held in place in the manner best shown in Figure 6 of the drawings wherein 15 designates an upright bracket member applied to the front face of the brush bearing bar made up of the angle bars 8 and 9. A pair of bolts 16 are employed to hold the bracket in place, and each of these bolts extends through a vertical slot 17 in the bracket 15 and also through the slot 11 in the brush bearing bar, whereby the bracket may be adjusted vertically. At the top of the bracket 15 there is a horizontal

slot 18 which receives the end of the angle bar 9. The angle bar 9 is secured to the bracket 15 by a bolt 19 which extends through the bracket 15 and through the angle bar 9 and is held in place by a lock washer 20. The angle bar 8 is secured to the bracket 15 by a bolt 21 which extends through the bracket 15 and through the angle bar 8 and is held in place by a lock washer 22. The angle bar 8 is secured to the angle bar 9 by a bolt 23 which extends through the angle bar 9 and through the angle bar 8 and is held in place by a lock washer 24. The angle bar 8 is secured to the angle bar 9 by a bolt 25 which extends through the angle bar 9 and through the angle bar 8 and is held in place by a lock washer 26. The angle bar 8 is secured to the angle bar 9 by a bolt 27 which extends through the angle bar 9 and through the angle bar 8 and is held in place by a lock washer 28. The angle bar 8 is secured to the angle bar 9 by a bolt 29 which extends through the angle bar 9 and through the angle bar 8 and is held in place by a lock washer 30. The angle bar 8 is secured to the angle bar 9 by a bolt 31 which extends through the angle bar 9 and through the angle bar 8 and is held in place by a lock washer 32. The angle bar 8 is secured to the angle bar 9 by a bolt 33 which extends through the angle bar 9 and through the angle bar 8 and is held in place by a lock washer 34. The angle bar 8 is secured to the angle bar 9 by a bolt 35 which extends through the angle bar 9 and through the angle bar 8 and is held in place by a lock washer 36. The angle bar 8 is secured to the angle bar 9 by a bolt 37 which extends through the angle bar 9 and through the angle bar 8 and is held in place by a lock washer 38. The angle bar 8 is secured to the angle bar 9 by a bolt 39 which extends through the angle bar 9 and through the angle bar 8 and is held in place by a lock washer 40. The angle bar 8 is secured to the angle bar 9 by a bolt 41 which extends through the angle bar 9 and through the angle bar 8 and is held in place by a lock washer 42. The angle bar 8 is secured to the angle bar 9 by a bolt 43 which extends through the angle bar 9 and through the angle bar 8 and is held in place by a lock washer 44. The angle bar 8 is secured to the angle bar 9 by a bolt 45 which extends through the angle bar 9 and through the angle bar 8 and is held in place by a lock washer 46. The angle bar 8 is secured to the angle bar 9 by a bolt 47 which extends through the angle bar 9 and through the angle bar 8 and is held in place by a lock washer 48. The angle bar 8 is secured to the angle bar 9 by a bolt 49 which extends through the angle bar 9 and through the angle bar 8 and is held in place by a lock washer 50. The angle bar 8 is secured to the angle bar 9 by a bolt 51 which extends through the angle bar 9 and through the angle bar 8 and is held in place by a lock washer 52. The angle bar 8 is secured to the angle bar 9 by a bolt 53 which extends through the angle bar 9 and through the angle bar 8 and is held in place by a lock washer 54. The angle bar 8 is secured to the angle bar 9 by a bolt 55 which extends through the angle bar 9 and through the angle bar 8 and is held in place by a lock washer 56. The angle bar 8 is secured to the angle bar 9 by a bolt 57 which extends through the angle bar 9 and through the angle bar 8 and is held in place by a lock washer 58. The angle bar 8 is secured to the angle bar 9 by a bolt 59 which extends through the angle bar 9 and through the angle bar 8 and is held in place by a lock washer 60. The angle bar 8 is secured to the angle bar 9 by a bolt 61 which extends through the angle bar 9 and through the angle bar 8 and is held in place by a lock washer 62. The angle bar 8 is secured to the angle bar 9 by a bolt 63 which extends through the angle bar 9 and through the angle bar 8 and is held in place by a lock washer 64. The angle bar 8 is secured to the angle bar 9 by a bolt 65 which extends through the angle bar 9 and through the angle bar 8 and is held in place by a lock washer 66. The angle bar 8 is secured to the angle bar 9 by a bolt 67 which extends through the angle bar 9 and through the angle bar 8 and is held in place by a lock washer 68. The angle bar 8 is secured to the angle bar 9 by a bolt 69 which extends through the angle bar 9 and through the angle bar 8 and is held in place by a lock washer 70. The angle bar 8 is secured to the angle bar 9 by a bolt 71 which extends through the angle bar 9 and through the angle bar 8 and is held in place by a lock washer 72. The angle bar 8 is secured to the angle bar 9 by a bolt 73 which extends through the angle bar 9 and through the angle bar 8 and is held in place by a lock washer 74. The angle bar 8 is secured to the angle bar 9 by a bolt 75 which extends through the angle bar 9 and through the angle bar 8 and is held in place by a lock washer 76. The angle bar 8 is secured to the angle bar 9 by a bolt 77 which extends through the angle bar 9 and through the angle bar 8 and is held in place by a lock washer 78. The angle bar 8 is secured to the angle bar 9 by a bolt 79 which extends through the angle bar 9 and through the angle bar 8 and is held in place by a lock washer 80. The angle bar 8 is secured to the angle bar 9 by a bolt 81 which extends through the angle bar 9 and through the angle bar 8 and is held in place by a lock washer 82. The angle bar 8 is secured to the angle bar 9 by a bolt 83 which extends through the angle bar 9 and through the angle bar 8 and is held in place by a lock washer 84. The angle bar 8 is secured to the angle bar 9 by a bolt 85 which extends through the angle bar 9 and through the angle bar 8 and is held in place by a lock washer 86. The angle bar 8 is secured to the angle bar 9 by a bolt 87 which extends through the angle bar 9 and through the angle bar 8 and is held in place by a lock washer 88. The angle bar 8 is secured to the angle bar 9 by a bolt 89 which extends through the angle bar 9 and through the angle bar 8 and is held in place by a lock washer 90. The angle bar 8 is secured to the angle bar 9 by a bolt 91 which extends through the angle bar 9 and through the angle bar 8 and is held in place by a lock washer 92. The angle bar 8 is secured to the angle bar 9 by a bolt 93 which extends through the angle bar 9 and through the angle bar 8 and is held in place by a lock washer 94. The angle bar 8 is secured to the angle bar 9 by a bolt 95 which extends through the angle bar 9 and through the angle bar 8 and is held in place by a lock washer 96. The angle bar 8 is secured to the angle bar 9 by a bolt 97 which extends through the angle bar 9 and through the angle bar 8 and is held in place by a lock washer 98. The angle bar 8 is secured to the angle bar 9 by a bolt 99 which extends through the angle bar 9 and through the angle bar 8 and is held in place by a lock washer 100.

flange or finger 18 overhanging the rack bar 12 so as to hold it in place on the slide-way constituted by the top of the brush bearing bar. Cooperating with the back of the rack bar 12 is a ball bearing anti-friction roller 19 mounted on a vertical axis 20 carried by an angle bracket 21 secured in place by the bolts 16. By reference to Figures 1 and 2 of the drawings it will be seen that the rack bar 12 is provided at each end with the form 5 of mounting shown in Figure 6.

The present apparatus is provided with a plurality of brushes 22. As the construction, mounting and operation is identical, a description of one of the brushes is deemed 10 sufficient. As best shown in Figure 5 of the drawings, it will be seen that each brush includes a head 23 having sets of bristles extending outwardly from the top and upright sides thereof. The bristles of the top 15 of the head are disposed so as to form an open topped socket surrounding the open top of a vertical axial passage 25 extending entirely through the brush-head. This 20 brush-head is supported upon the top of a tubular spindle 26 having an external annular shoulder 27 on which the bottom of the brush-head rests. A pin or key 28 extends radially across the bore or passage 25 in the 25 brush-head and rests in the notches 29 formed in the top of the tubular spindle 26. The weight of the brush holds it down against the shoulder 27, while the pin or key 28 interlocks the brush and the spindle 26 30 for simultaneous rotation. The brush may be conveniently applied and removed vertically with respect to the spindle 26 in a very convenient manner and grease may be fed through the tubular spindle into the socket 35 35 40 from which it will be conducted by absorption to all of the bristles of the brush. The lower portion of the spindle 26 rotates within an upright bearing 30 having a bore extending from the top to the bottom of the bearing. Wings or flanges 31 are provided 45 at opposite sides of the bearing 30 and are pierced by headed bolts 32, each of which extends through the slot 11 in the slideway for the rack bar. The threaded inner end 50 of each bolt 32 engages a threaded opening in a nut or plate 33 at the back of the slideway, whereby the bearing 30 is secured in place and may be adjusted longitudinally along the slideway. Within the lower portion 55 of the bore of the bearing 30 there is an internal annular shoulder 34 for the support of suitable packing 35. The lower end of the tubular spindle is internally beveled as at 36, and rests upon the packing 35 so as 60 to crowd the packing against and around a nozzle 37 which extends upwardly through the lower portion of the spindle 36 and is fixed to the bearing 30 below the shoulder 34, as by being threaded to the inner walls of 65 the bearing 30. Immediately above the top

of the bearing 30, a pinion 39 is provided upon the spindle 36 and is in mesh with the teeth of the rack bar 12, so that when the latter is reciprocated, the pinion 39 will be rotated first in one direction and then in the 70 opposite direction for the purpose of imparting the same motion to the brush carried at the top of the spindle.

An elbow fitting 40 is provided at the bottom of the bearing 30 and in communication 75 with the bottom of the stationary nozzle 37, it being understood that the bottom portion of the tubular spindle 26 rotates between the stationary nozzle 37 and the stationary bearing 30.

Grease is supplied to the open bottom of the nozzle 37 through an elbow 40 fitted to the bottom of the bearing and provided with a coupling 41 to which is secured a hose or flexible tube 42. The lower end of the flexible tube 42 communicates with a suitable valve 43 carried by a horizontal manifold suitably-mounted upon the shelf or partition 7. One end of this manifold is provided with a down-turned elbow 45 connected to the top of a pipe 46 best shown in Figure 4 of the drawings and extending downwardly through an opening in the shelf and communicating at its lower end with the barrel 47 of a pump, which pump-barrel is suitably 90 suspended from the shelf or partition 7. A piston or plunger 48 works in the pump barrel 47 and projects above the top of the latter and through a suitable gland 49. Within the bottom portion of the pump barrel is a helical spring 50 which bears upwardly against the bottom of the plunger 48 to maintain the latter normally in an elevated position. The bottom of the pump barrel is provided with an inlet valve 51 opening through the pump barrel and communicating with the lower portion of a removable grease receptacle 52. The plunger 48 is operated by means of a foot lever or treadle 53 mounted below the grease receptacle and fulcrumed at 54 on one of the frame bars 4. The front end of the lever projects at the front of the frame and is provided with a foot piece 55 disposed in convenient reach of the foot of the operator. The lever 53 is guided at its free end by a guide member 56 extending laterally from the lever and provided with a pair of spaced fingers working at opposite sides of the adjacent leg standard 1 so as to prevent side-wise movement of the lever. A connecting rod 58 rises from the lever 53 and extends through an opening 59 in the partition 7 and has its upper end connected to one end of a cross-head 60 pivoted intermediate of its ends, as at 61, to the top of the plunger 48, the other end of the cross-head 60 being pivoted to an upstanding link 62 suitably 100 fulcrumed at 63 to the frame of the apparatus. 105

The grease receptacle 52 is open at its top, houses the lower portion of the pump and is clamped up against the bottom of the partition 7 which closes the open top of the tank or receptacle. For the support of the grease receptacle there is a horizontal bar 64 disposed beneath the receptacle and pivoted at 65 upon the lower rear cross-bar 4, while its front free end portion rests removably upon the front cross-bar 4. Interposed between the bar 64 and the bottom of the receptacle 52 is a bracket 66 on which the receptacle 52 rests, there being an electric heating pad 67 interposed between the bracket 66 and the bottom of the receptacle 52. The electric conductors 68 lead from the pad to a suitable switch 69 provided upon the exterior of one end of the frame of the apparatus. Suitable legs 70 depend from the bracket 66 and fit in sockets or openings 71 in the bar 64. A set screw 72 extends upwardly through the bar 64 and engages the bottom of the bracket 66 so as to force the latter against the bottom of the grease tank 52 and removably clamp the latter against the shelf or partition 7. By backing off the clamping screw 72, the bracket 66 may be lowered and the bar 64 swung to the back of the machine thereby to permit of the grease tank 52 being lowered until it clears the bottom of the pump, whereupon the grease tank may be removed.

When the foot lever 53 is depressed, the pump plunger 48 will be forced downwardly, and a charge of grease will be forced through the pipe 46 into the manifold 44 from which the grease will be forced through the respective tubes 42 into the tubular spindles 26 and then into the brushes. When pressure is removed from the foot lever 53, the spring 50 will lift the plunger 48 and draw grease through the valve 51 into the pump cylinder, thereby to charge the latter preparatory to again supplying grease to the brushes when required. The housing of the spring 50 within the pump is advantageous in that it cannot become displaced or out of order and a prompt and efficient lift of the pump plunger 48 is assured. The pipe 46 is provided with a check valve 73 to prevent the return of grease from the manifold 44 into the pump cylinder.

Should any one of the tubes 42 or tubular spindles 26 become choked it can be readily cleared by removing the grease tank 52, closing all of the valves 43 of the manifold 44 and manipulating the foot lever 53 to compress air in the manifold 44, after which the proper valve 43 is opened so as to admit air pressure into the desired tube 42 and thence through the tubular spindle 26. The pressure which can be produced within the manifold 44 will be sufficient to clear out any

obstructions which may lodge in a tube 42 and its communicating spindle 26.

For the purpose of reciprocating the rack bar 12 there is provided an electric motor 74 having a pinion 75 meshing with a gear 76, the shaft of which drives a pinion 77 which in turn engages a large gear 78 having a crank member 79 working in the vertical slot of a cross-head 80 depending from the rack bar 12. The movement of the crank member 79 in the slot or slideway of the cross-head 80 will reciprocate the rack bar 12 in a simple and efficient manner. The cross-head 80 is guided in its movement by the crank wheel 78 lying at one side of the cross-head and a guide element 81 carried by the partition 7 and lying at the opposite side of the lower end portion of the cross-head which latter depends below the crank gear 78.

In using the present apparatus, the operator takes a set of pans, commonly five in number rigidly connected by connecting bars, inverts the same and places them downwardly upon the brushes, one brush within each pan. The electric motor 74 is started by throwing the switch 82, whereupon the brushes will be rotated first in one direction and then in the opposite direction and the operator moves the pans back and forth across the brushes which apply a thin coating of grease to the interior bottom and side walls of the pans. Grease is supplied to the brushes from time to time by manipulating the foot lever 53. The grease is heated and maintained in a thin condition by the electric heater 67. The brushes are rotated at about forty revolutions per minute which has been found sufficient to properly apply the grease without scattering the grease, and therefore loss of grease is effectually prevented in the operation of the machine of the present invention. Furthermore the grease is uniformly distributed to the brushes and uniformly applied to the pans in a very thin coating sufficient for baking purposes, whereby the present apparatus uses the minimum amount of grease and at the same time applies an adequate amount of grease to the pans, thereby resulting in a material saving of grease over the hand method of greasing pans.

The frame of the machine is provided with a top plate 83, as shown in Figure 1 of the drawings and this plate is provided with a longitudinal slot 84 to accommodate the brush spindles 26. Each brush spindle is provided with a cover plate 85 having an opening 86 through which the brush spindle projects. One end of the cover plate is provided with a bifurcation 87, and the cover plate is wide enough to cover the slot 84 in the top of the machine and long enough to lap the adjacent cover plate and to receive the adjacent brush spindle in the

bifurcation. The top plate 83 and the several cover plates 85 prevent grease from dropping down upon the working parts of the machine below the top plate.

5 Each of the spindles 26 may be removed by pulling it upwardly out of its bearing 30, whereby one or more of the brushes and their spindles may be removed when not required, as when greasing a single pan or 10 a number of pans less than the total number of brushes. When removed, the brush may be separated from its spindle and placed upon the partition 7 at either end portion of the machine, and the spindle may 15 be thrust downwardly through any one of a series of openings 88 in the partition 7 until its gear 39 rests as a shoulder upon the partition 7 so as to support the spindle in a conveniently accessible condition.

20 The upper portion of the frame, above the partition 7 may be enclosed on all four sides, the front plate 89 constituting a door which may be hinged as at 90 to the adjacent bar 5, whereby the plate or door 89 25 may be swung outwardly and downwardly to give access to the various parts of the machine lying between the top plate 83 and the shelf or partition 7.

Lard is preferred as the greasing element 30 for baking pans. In order that lard may be pumped, it is first necessary to reduce it to liquid form by heating the same. Heated grease will clean a pan better than cold grease.

35 In the present invention, I employ a single manifold 44 with separate and independent conduits 42 leading therefrom to the respective brushes, each conduit being provided with a valve or pet cock 43. The lard 40 receptacle 52 is quickly detachable or removable, and a single pump 48 is mounted independently of the lard receptacle but extending thereinto and communicating with the manifold. By this arrangement a 45 single pump of large capacity may be employed, which is simpler and more satisfactory than the employment of a pump for each brush. By the employment of a single pump communicating with a manifold, the most uniform supply of grease to the 50 brushes may be obtained. If any one or more brushes is receiving too much grease, the supply may be cut down by adjustment of any one of the valves 43. Furthermore, 55 if any one of the conduits 42 becomes choked, it may be cleared out by closing the valves 43 of the other conduits and employing the full force of the pump on the one conduit 42.

60 The removability of the grease receptacle 52 enables the convenient cleaning thereof and gives ready access to the pump for cleaning the same, whereby these portions of the apparatus may be maintained in a sanitary 65 condition. Furthermore, the removal

of the grease receptacle 52 enables the convenient supply of lard thereto.

What is claimed is:

1. A pan greasing machine, comprising an upright tubular rotatable brush spindle, 70 a removable brush carried by the spindle and in communication with the interior thereof, means for rotating the brush, and means for feeding grease through the spindle to the brush, the brush end of the spindle having a notch, and the brush having a spindle receiving bore and a pin carried by the brush and extending across the bore and seated in the notch.

75 2. A pan greasing machine comprising an upright tubular brush spindle provided in its top with a notch, a removable brush having a bore receiving the top of the spindle and provided with a pin extending across the bore and seated in the notch, means for feeding grease to the brush through the spindle, and means for rotating the spindle.

80 3. A pan greasing machine, comprising an upright rotatable tubular spindle, a brush carried by the spindle, a bearing rotatably supporting the spindle, a nozzle carried by the bearing and extending longitudinally into the bottom of the spindle, packing below the spindle and between the bearing and the nozzle, and grease supplying means in 85 communication with the nozzle.

90 4. A pan greasing machine having a brush and means for feeding grease to the brush including a grease receptacle and a pump mounted therein, and provided with a spring to retract the pump plunger, said spring being mounted within the pump barrel between the plunger and the pump inlet and exposed to the contents of the pump barrel.

95 5. In a pan greasing machine, the combination with a frame having a horizontal shelf, of a brush mounted above the shelf, a grease receptacle below the shelf, a pump supported by the shelf and extending into the grease receptacle, a delivery connection between the pump and the brush, and means for actuating the pump.

100 6. In a pan greasing machine, the combination of a frame having a shelf, a brush mounted above the shelf, a grease receptacle removably clamped against the bottom of the shelf, a pump carried by the shelf and extending into the grease receptacle, means for operating the pump, and a delivery connection between the pump and the brush.

105 7. In a pan greasing machine, the combination of a frame having a shelf, a brush mounted above the shelf, a grease receptacle removably held against the bottom of the shelf, a pump carried by the shelf, and extending into the grease receptacle, a bar pivoted to the frame and also pivotally connected to the pump plunger, a foot lever fulcrumed on the frame, and an operating 110

connection between the foot lever and the pivoted bar.

8. In a pan greasing machine, the combination of a frame, a brush thereon, a grease receptacle, a pump for supplying grease from the receptacle to the brush, and releasable means for supporting the grease receptacle and including a heating element.

9. In a pan greasing machine, the combination of a frame having a shelf, a brush mounted above the shelf, a grease receptacle below the shelf, means for removably holding the grease receptacle against the bottom of the shelf, an electric heating element carried by the holding means in cooperative relation with the grease receptacle, and a pump for feeding grease from the receptacle to the brush.

10. In a pan greasing machine the combination of a frame having a shelf, a brush above the shelf, a grease receptacle below and against the shelf including a displaceable cross-bar, a bracket between the cross-bar and the bottom of the grease receptacle, a clamping member carried by the cross-bar in cooperative relation with the bracket to force the latter against the bottom of the grease receptacle, and means for supplying grease from the receptacle to the brush.

30 11. A pan greasing machine, comprising upright rotatable tubular spindles, a brush carried by each spindle, a bearing rotatably supporting each spindle, a nozzle carried by each bearing and extending longitudinally into the bottom of the spindle carried by said bearing, packing within each bearing and between the bottom of the spindle and the nozzle, and a grease pump communicating with the several nozzles.

40 12. A pan greasing machine, comprising upright rotatable tubular spindles, a brush carried by each spindle, a bearing rotatably supporting each spindle, a nozzle carried by each bearing and extending longitudinally into the bottom of the spindle carried by said bearing, packing within each bearing and between the bottom of the spindle and the nozzle, a manifold, conduits leading from the manifold to each nozzle, and a grease pump communicating with the manifold.

50 13. In a pan greasing machine, the combination of a brush, a quick detachable grease receptacle, a pump mounted independently of the receptacle and in communication therewith, pump operating means, and a delivery connection between the pump and the brush.

JACOB S. ALLEN.
